UNITED STATES PATENT OFFICE

138,667

DESIGN FOR A TOY COMMANDO TOMMY GUN

Oliver S. Annable, Brooklyn, N. Y., assignor of one-half to Spotswood Specialty Company, Inc., Lexington, Ky., a corporation of Kentucky

Application March 18, 1943, Serial No. 109,774

Term of patent 7 years

(Cl. D34—15)

To all whom it may concern:

Be it known that I, Oliver S. Annable, a citizen of the United States, residing at Brooklyn, in the Borough of Brooklyn and State of New York, have invented a new, original, and ornamental Design for a Toy Commando Tommy Gun, of which the following is a specification, reference being had to the accompanying drawing, forming a part thereof.

commando tommy gun showing my new design.

I claim:

The ornamental design for a toy commando tommy gun, as shown.

OLIVER S. ANNABLE.
